CARRYING CASE

Frank A. Hoffman, % Arvin Industries, Inc.,
Columbus, Ind.

Filed Sept. 1, 1960, Ser. No. 61,976

Term of patent 14 years

(Cl. D87—5)

FIG. 1 is a perspective view of a carrying case, showing my new design;

FIG. 2 is a perspective view of the carrying case shown in FIG. 1 showing the handle extended to the position of a shoulder strap, a portion of said strap being broken away for convenience of illustration;

FIG. 3 is a bottom plan view of the carrying case shown in FIG. 1;

FIG. 4 is a bottom plan view of the carrying case shown in FIG. 2;

FIG. 5 is a perspective view of the carrying case shown in FIG. 1, but with the case in open position;

FIG. 6 is an end elevation of the carrying case shown in FIG. 1; and

FIG. 7 is an end elevation of the carrying case shown in FIG. 2, a portion of the handle strap being broken away for convenience of illustration.

The characteristic feature of my design resides in the extensible handle with end-attached stops mounted within the beads of a circumferential moulding strip so as to be converted from hand-carrying position to shoulder-carrying position by release of the said stops from their bottom attaching means, as shown.

I claim:

The ornamental design for a carrying case, as shown and described.
